UNITED STATES PATENT OFFICE

2,416,345

VALVE AND AIR CHARGER FOR PUMPS
AND STORAGE TANKSJack E. Piccardo, Oakland, Calif., assignor to
Shasta Pump Company, a corporation of California

Application August 5, 1944, Serial No. 548,233

19 Claims. (CL 103—6)

1

The invention relates to valve mechanisms and to air pump or charging means adapted for use with a well pump and storage tank therefor wherein a predetermined quantity of water or other well fluid is automatically supplied to and maintained in the tank under a predetermined air pressure head as the water or other fluid is withdrawn for use from the tank.

In water pressure systems to which the present invention is related, the water supply in the storage tank will vary between predetermined levels, there being at all times provided over the water level a head or cushion of compressed air. As water is withdrawn from the tank, the water level drops with a corresponding expansion and reduction of pressure of the air cushion. When the water supply and pressure are thus reduced in the tank to a predetermined amount, usually about 20 lbs. per sq. inch pressure, the pump is automatically started and the water in the tank replenished to a predetermined quantity and pressure, usually about 40 lbs. per sq. inch, when the operation of the pump is automatically stopped. Because air is lost by absorption into the water and otherwise, the air cushion in the tank must be recharged with additional air. An object of the present invention is to provide a valve mechanism and air charger of the character described in which a positive displacement air pump is unitarily combined with and motivated by a pressure responsive valve mechanism connected between the pump and storage tank whereby the establishing of communication between the pump and tank during operation of the pump and the charging of the tank with air during each pump operation will be automatically accomplished.

Another object of the invention is to provide a valve mechanism of the character described which is adapted for use in a deep well system using an ejector pump in the bottom of the well for elevating the water to a centrifugal or other type pump located at or near the surface of the well, and wherein the valve mechanism is designed to provide a sufficient back pressure in the discharge passage of the centrifugal pump to insure proper operation of the ejector pump. As a further object of the invention, the valve mechanism herein provided may be adjusted to provide an optimum back pressure for the particular installation in which it is used.

Still another object of the invention is to provide in a device of the character described, a novel and efficacious design, construction and arrangement of parts including a minimum number of sturdily formed parts assembled in a single cas-

2

ing or housing and coating to provide the pressure responsive valve means and the air pump means hereinabove described.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawing:

Figure 1 is a side elevation, somewhat diagrammatical, of a deep well pressure water pump and storage system incorporating the valve and air pump mechanism of the present invention.

Figure 2 is a longitudinal sectional view of the valve and air charger unit.

Figure 3 is a longitudinal sectional view of the unit shown in Figure 2 but taken at substantially right angles thereto.

Figure 4 is a cross-section view of the unit taken substantially on the plane of line 4—4 on Figure 3.

The valve and air charger unit 6 of the present invention is adapted for use with a water pressure system such as illustrated in Figure 1 of the drawing. This system includes a centrifugal pump 7 mounted at the surface of a well shaft 8, driven by an electric motor 9, having an intake column or suction pipe 11 connected thereto extending to the bottom of the well, and having a discharge passage 12, here connected by pipe 13 to the unit 6. A pipe 14 connects unit 6 to a storage tank 16 adapted to receive and store under pressure water or other fluid delivered by the pump 7, the tank being provided with an outlet 17 for connection to the service lines with which the system is used. Provided at the bottom of the intake column 11 is an ejector pump 20 including a Venturi chamber or tube 18 at the lower end of the column 11 which coacts with an upturned nozzle 19 for forcing the well fluid into the column 11 with sufficient pressure to elevate the fluid to an operating level with respect to the centrifugal pump 7. The nozzle 19 is connected to the lower end of a pressure delivery pipe 21 extending into the well from the discharge passage 12 of the centrifugal pump 7. Connected to the chamber 18 for admitting well fluid, is a foot or check valve 22 which opens to admit well fluid when the pump 7 is in operation and a reduced pressure is thereby created in the chamber 18; and closes to seal

off the pump lines 11 and 12 and the chamber 18 from the well fluid on discontinuance of pump operation. A pressure responsive electric switch mechanism 23, having a pressure connection 24 to the tank and an electrical connection 26 to the electric motor 9 and source of electric power, is constructed and operates in the usual manner to cause the motor to be energized when the water level and air pressure in the tank fall to a predetermined minimum level 27 (commonly set at about 20 lbs. per sq. inch), and to shut off the power connection to the motor when the water level and pressure in the tank have been raised to a predetermined maximum level 28 (commonly set at about 40 lbs. per sq. inch). If desired, a usual air vent valve 29 may be provided on the tank at the maximum water level so as to vent off excess air which may accumulate in the tank.

The valve and air charger unit 6 as illustrated in Figures 2 to 4, comprises briefly the combination of a valve part 31 operatively positioned in the passage between the pump 7 and the tank 16 and movable to positions opening and closing such passage, a pressure responsive actuator 32 hydraulically connected to the pump 7 and motivated by the pressure differential generated thereby to displace the valve part into its open and closed positions, and an air pump means 33 operatively connected to the valve part and pressure responsive actuator and displaced thereby for pumping air under pressure into the tank.

Preferably the several operating elements of the unit 6 are unitarily assembled in a single housing or casing 34, here composed of a generally hollow center section 36 and end sections or covers 37 and 38. Secured peripherally to the opposite ends of the center section 36 at the covers or end walls 37 and 38, are flexible diaphragms which here provide the pressure responsive and pump elements 32 and 33, and define with the end walls 37 and 38, end chambers 39 and 41 of variable volume depending upon the relative endwise position of the diaphragms. An intermediate wall 42 is provided across the interior of the casing between the diaphragms 32 and 33 to provide therewith a pair of interior chambers 43 and 44 adapted for connection, by fittings 46 and 47 provided by the casing section 36, to the tank 16 and the discharge passage 12 of the pump 7 respectively. The end chamber 41, separated from the high pressure chamber 44 by diaphragm 32, is adapted for connection to a relatively reduced pressure point at the pump 7. For this purpose the adjacent end wall 38 is provided with an opening 48 for connection as by conduit 49 to the pump suction pipe 11. Where a multi-stage centrifugal pump is used, the conduit 49 may be connected to an intermediate stage rather than the pump intake. In either event, the function of the connection is to utilize a pressure differential generated by the pump when in operation to operatively displace the pressure responsive element 32 by applying the pressure differential to the opposite sides thereof in chambers 41 and 44. Thus when the pump is in operation, the pressure differential generated thereby will displace diaphragm 32 toward the end chamber 41. Mounted in the end chamber 41 between the end wall 38 and the diaphragm 32, is a helical spring 51 which is compressed upon movement of the diaphragm 32 into the chamber 41 during operation of the pump, and which returns the diaphragm 32 to its opposite displaced position into chamber 44 upon stopping of operation of the

75 pump when the pressures in chambers 41 and 44 equalize.

Fluid flow through the unit from the pump to the storage tank is effected through an opening 52 provided in the intermediate wall 42 connecting the pump chamber 44 with the tank chamber 43. Preferably and as here shown this opening is positioned in longitudinal alignment with the centers of the diaphragms 32 and 33 and is formed to slidably receive the valve part 31 which is here of cylindrical shape to fit the opening and is connected at its opposite ends to center portions of the diaphragms 32 and 33. Fluid flow through the opening 52, normally prevented by the positioning of the valve part therein, is permitted upon movement of the valve part to place a fluted portion 53 of the valve part in the opening. The fluted portion 53 is here formed of a plurality of circumferentially spaced channels 54 having a longitudinal dimension somewhat longer than the thickness of wall 42 at the opening 52. Desirably the bottom wall 56 of each channel is sloped to the cylindrical periphery of the valve part so as to provide a conical like opening through the fluted portion upon initial opening of the valve part as illustrated in Figure 3, to thereby afford better regulation of the size of the passage through the opening 52 in the partial open positions of the valve part.

The variable end chamber 39 here provides the air pump chamber for the unit and is provided with an air intake passage 57, formed in the end cover 37, and adapted for connection to the atmosphere. An air intake check valve 58 (here of the type used in automobile tire tubes) is mounted in the passage 57 and functions to admit air upon expansion of the chamber 39 and to close upon filling the chamber and during contraction thereof. Also formed in the end cover 37, is an air discharge passage 59 which communicates the air pump chamber 39 with the adjacent tank chamber 43. The passage 59 is here reduced as at 61 to provide a constriction to the water flow therethrough from the tank chamber 43 into the air chamber 39 so that upon the rapid expansion of the air chamber, air will be drawn into the chamber through check valve 58. On subsequent contraction of the air pump chamber, the air thus introduced and also any excess water which has entered through passage 59, are forced out of the pump chamber 39, through passage 59, into the tank chamber 43, for ultimate passage to the tank.

Connection of the valve part 31 to the diaphragm 33 may be effected in any suitable manner so as to maintain thereat the seal between the tank and air pump chambers 43 and 39. As here shown, reenforcing plates 63 and 64 are mounted on opposite sides of the diaphragm and are secured with the diaphragm to the adjacent end face of the valve part 31 by means of a machine screw 66. Connection of the opposite end of valve part 31 to the diaphragm 32 is effected in a similar manner by means of reenforcing plates 67 and 68 and a hollow screw 69 having a center bore 71 which registers with a longitudinal recess or chamber 72 provided in the adjacent end of the valve member 31. Mounted in the chamber 72 for longitudinal reciprocation therein is a plunger 73 which is normally urged to an outwardly displaced position against the screw 69 by a helical spring 74 mounted in the chamber between the plunger 73 and the inner end 76 of the chamber. A stem 77 secured to and extending axially from the end cover 38 in alignment with

the bores 71 and 72, is adapted to enter the bore 71, upon movement of the diaphragm 32 into the chamber 41, to engage and displace the plunger 13 against the resilient resistance of the spring 74. As an important feature of the present construction the stem 71 is adjustable longitudinally so as to control the resilient resistance to the full opening of the valve passage 52. As here shown the stem 71 is threaded through the end cover 38 and is engageable at its outer end 78 for turning to effect its longitudinal adjustment. A cap 79 is preferably detachably secured to the end cover in enveloping relation to the stem end 78 to prevent undesirable tampering with the adjustment.

If desired a priming opening 81, normally closed by threaded plug 82, may be provided in the casing at the pump chamber 44 to permit initial priming of the pump.

Operation

The position of the several parts of the unit during the normal period of inactivity of the pump 7, when the water level and pressure in the tank is above the predetermined level 27, is shown in Figure 2. When the pump 7 is not in operation, foot valve 22, at the bottom of the pump intake and discharge columns 8 and 11, is closed; the pump discharge and intake pressures in chambers 44 and 41 are equalized; the pressures in the air pump chamber 39 and the tank chamber 43 are equalized through the connecting passage 59; and the diaphragm 32 and connected valved part 31 and diaphragm 33 are displaced by the spring 51 to the closed position of the valve member and the contracted position of the air pump chamber 39. In this position of the parts, chambers 41 and 43 are relatively expanded and chambers 44 and 39 are relatively contracted.

As water is used from the tank and the water level and pressure are reduced to the predetermined minimum, the pressure responsive electric switch 23 closes to cause energizing of the electric motor 9 and operation of the pump 7. The pressure differential generated by the pump and applied to chambers 44 and 41 rapidly displaces the diaphragm 32 against the resistance of spring 51 to register the fluted portions 53 of the valve member with the opening 52, thereby opening the passage between the pump discharge chamber 44 and the tank. This position of the parts is illustrated in Figure 3. It will be noted that as the fluted portion of the valve member approaches the valve opening, the stem 71 is engaged by the spring pressed plunger 13 to limit the opening of the valve as a function of the pressure differential generated by the pump and to thereby maintain a requisite back pressure in the discharge column 8 for proper operation of the ejector pump 20. In the movement of the parts from the position illustrated in Figure 2 to position illustrated in Figure 3, the air chamber 39 is expanded and air admitted thereto through the inlet check valve 58 as above described.

As the water level and pressure in the tank are raised to a predetermined maximum, the pressure responsive switch 23 opens and operation of the pump 7 stops. With the stopping of the pump, foot valve 22 closes, the pressures in chambers 44 and 41 equalize, and the spring 51 displaces the diaphragm 32 thereby moving the valve member to a closed position in the valve opening 52 and compressing the air pump chamber to its contracted position as shown in Figure 2. On

contraction of the chamber 39, air is pumped through the discharge passage 59 into the tank chamber 43 for passage to the tank.

In shallow well pump installations, the ejector pump 20 may be eliminated or in any event the back pressure in the discharge line reduced to a minimum. In such an installation, the stem 71 is preferably backed away from the diaphragm 32, or the stem and associated plunger 13 and spring 74 may be removed, to permit a maximum opening of the valve passage 52. Thus, generally, the stem 71 is advanced or retracted in proportion to the depth of the well, and usually only needs be set at time of installation.

It will be noted from the drawings that during the operation of the pump, the tank pressure in chamber 43 on one side of diaphragm 33 is balanced by an equal pressure in the air pump chamber 39 on the opposite side of the diaphragm by reason of the connecting passage 59 so that the tank pressure is neutralized insofar as its effect on movement of the valve is concerned. Thus, the size of the air pump diaphragm 33 may be selected either larger or smaller than the actuator diaphragm 32 in accordance with the amount of air desired to be pumped.

I claim:

1. In combination with a pump and a tank for storing under pressure fluid pumped thereby; a pressure responsive valve mechanism adapted for connection to said pump and to said tank and having a valve part motivated by the pressure differential generated by said pump and co-acting with passages provided in said mechanism to open and close fluid passage from said pump to said tank as said pump is and is not in operation, and air pump means connected to and operatively displaced by said valve part for pumping air under pressure into said tank.
2. In combination with a pump and a tank for storing under pressure fluid pumped thereby; a valve mechanism comprising, a housing having intake and discharge passages adapted for connection to the discharge passage of said pump and to said tank respectively, a valve part movable into positions permitting and preventing registration and communication of the aforesaid housing passages, pressure responsive means mounted in said housing and connected to said valve part and adapted for connection to pressure differential points on said pump and operated by the pressure differential at said points generated by said pump when in operation to move said valve part to its aforesaid passage opening position and operable on discontinuance of said pressure differential to move said valve part to its aforesaid passaged closing position, and air pump means connected to and motivated by said pressure responsive means for pumping air under pressure into said tank.
3. In combination with a pump and storage tank; a regulating valve and air charger comprising a valve casing having a passage adapted for connection between the output of said pump and said tank, a valve part mounted in said casing and movable to positions opening and closing said passage, spring means normally urging said valve part to closed position, pressure responsive means connected to said valve part and having passages adapted for connection to relative intake and discharge passages of said pump and being operated by pressure differential generated by said pump when in operation for moving said valve part to open position against the resistance of said spring, and air

pump means having a discharge passage for connection to said tank and being connected to and operatively displaced by said valve part for pumping air into said tank.

4. In combination with a pump and tank for storing under pressure fluid pumped thereby; a valve casing having a passage adapted for connection to said pump and said tank, a valve part mounted in said casing and movable to positions opening and closing said passage, spring means normally urging said valve part to closed position, pressure responsive means connected to said valve part and having passages adapted for connection to relative intake and discharge passages of said pump and being operated by pressure differential generated by said pump when in operation for moving said valve part to open position against the resistance of said spring, and a positive displacement air pump adapted for connection to said tank and having a reciprocating air displacing part operatively connected to said pressure responsive means, the design of said air pump being such that said air displacing part will move through an intake stroke during movement of said valve part to open position and will move through a discharge stroke during movement of said valve part to closed position.

5. In combination with a pump and tank for storing under pressure fluid pumped thereby; a valve casing having a passage adapted for connection to said pump and said tank, a valve part mounted in said casing and movable to positions opening and closing said passage, spring means normally urging said valve part to closed position, pressure responsive means connected to relative intake and discharge passages of said pump and being operated by pressure differential generated by said pump when in operation for moving said valve part to open position against the resistance of said spring, and a diaphragm mounted in said casing and defining with portions thereof an air pump chamber having inlet and discharge passages adapted for connection to the atmosphere and said tank respectively, said diaphragm being operatively connected to and displaced by said valve part to change the volume of said pump chamber upon movement of said valve part to its positions aforesaid.

6. In combination with a pump and a tank for storing under pressure fluid pumped thereby; a regulating valve and air charger comprising, a casing having inlet and discharge chambers adapted for connection to the discharge passage of said pump and said tank respectively and formed with a valve passage connecting said chambers, a diaphragm mounted in said casing with one side thereof in communication with said inlet chamber, the opposite side of said diaphragm defining with portions of said casing a low pressure chamber adapted for connection to the intake passage of said pump whereby the pressure differential generated by said pump when in operation will cause said diaphragm to move in the direction of said low pressure chamber, a valve movable to positions opening and closing said valve passage and being connected to said diaphragm and displaced thereby to open position upon movement of said diaphragm as aforesaid on operation of said pump, spring means urging said diaphragm and valve to a closed position of said valve on discontinuance of pump operation, and a second diaphragm defining with portions of said casing an air pump chamber having intake and discharge passages adapted for connection to the atmosphere and

said tank respectively, said second diaphragm being connected to said valve and movable therewith to produce a volumetric change in said air pump chamber.

5 7. In combination with a pump and a tank for storing under pressure fluid pumped thereby; a regulating valve and air charger comprising, a casing, a pair of flexible diaphragms peripherally secured to said casing adjacent opposite walls thereof to define with said walls end chambers of variable volume, an interior wall extending across said casing between said diaphragms and defining therewith a pair of interior chambers, said interior wall being formed with a valve passage, means for connecting said valve passage between the discharge passage of said pump and said tank, the pump side of said valve passage being connected to one of said interior chambers, means for connecting the adjacent end chamber to the intake passage of said pump, a valve member mounted in said valve passage and being connected to said diaphragms to provide joint movement thereof between positions of said valve member respectively opening and closing said valve passage, the pressure differential generated by said pump when in operation and acting in said last named interior chamber and adjacent end chamber functioning to move said valve member to open position, and spring means urging said valve member to closed position on discontinuance of operation of said pump, the other end chamber having passages adapted for connection to the atmosphere and said tank coacting with the volumetric change of said last named end chamber to pump air into said tank.

30 8. A mechanism as defined in claim 7 wherein said valve member is formed with a longitudinal recess extending to an end thereof and through the diaphragm secured thereto at the end chamber connected to the intake passage of said pump, a helical spring mounted in said recess, a stem member secured to said adjacent end wall in longitudinal alignment with said recess and adapted to enter said recess and engage and compress said spring upon movement of said valve member toward said end wall to the open position of said valve member, and means for adjusting the longitudinal position of said stem member for controlling the amount of opening of said valve member.

45 9. In combination with a pump having inlet and discharge passages and a storage tank, a valve casing having a passageway connected between said discharge passage and said tank, a valve movably mounted in said passageway to control the fluid flow therethrough, spring means normally urging said valve towards a closed position of said passageway, a pressure actuator connected to said valve and having passages connected to the inlet and discharge passages of said pump and operated by the pressure differential generated by said pump when in operation to displace said valve toward an open position of said passageway against the resistance of said spring means, and a variable air pump chamber having an air discharge passage connected to said tank and connected to and contracted and expanded by the operation of said spring means and pressure actuator to pump air into said tank.

60 10. A regulating valve and air charger for a pump and storage tank comprising, a body having intake and discharge passages and a connecting valve passage, a valve part operatively positioned in said valve passage and functioning on displacement to regulate the flow in said valve pas-

sage, a pressure responsive actuator including relatively high and low pressure chambers and an element therebetween displaced by the pressure differential between said chambers, said element being connected to said valve part, an air pump including an air chamber and a volumetric displacement member therein, means connecting said member to said actuator element for displacement thereby, and air intake and discharge means connected to said air chamber, said air discharge means being connected to said first named discharge passage.

11. A regulating valve and air charger for a pump and storage tank comprising, a body having intake and discharge passages and a connecting valve passage, a valve part operatively positioned in said valve passage and functioning on displacement to regulate the flow in said valve passage, a pressure responsive actuator including relatively high and low pressure chambers and an element therebetween displaced in one direction by pressure differential between said chambers, spring means urging said element in an opposite direction, said element being connected to said valve part, and air pump means connected to and operatively displaced by said valve part and having an air discharge passage connected to said first named discharge passage.

12. A regulating valve and air charger for a pump and storage tank comprising, a body having intake and discharge passages and a connecting valve passage, a valve part operatively positioned in said valve passage and functioning on displacement to regulate the flow in said valve passage, a pressure responsive actuator including relatively high and low pressure chambers and an element therebetween displaced by the pressure differential between said chambers, said element being connected to said valve part, an air pump including an air chamber and a volumetric displacement member therein, means connecting said member to said actuator element for displacement thereby, atmospheric air intake means for said air chamber, and air discharge means for said chamber connected to said first named discharge passage.

13. A pressure responsive device of the character described comprising, a casing, a pair of flexible diaphragms peripherally secured to said casing adjacent opposite walls thereof to define with said walls end chambers of variable volume, an interior wall extending across said casing between said diaphragms and defining therewith a pair of interior chambers, said interior wall being formed with a valve passage, a valve member connected to said diaphragms to provide joint movement thereof between positions of said valve respectively opening and closing said valve passage, said valve member being movable to open position on application of a pressure differential to one of said end chambers and one of said intermediate chambers, and spring means urging said valve member to closed position on discontinuance of said pressure differential.

14. A pressure responsive air charger and valve mechanism comprising, a casing divided into first, second, third and fourth chambers by a flexible diaphragm spaced from each end thereof and a wall between said diaphragms, an opening through said wall and a valve member to open and close said opening, said valve connected to and moving in unison with said diaphragms, means to normally position said valve member to closed position to cause the inner chamber at one end to be contracted and the outer chamber

at said end to be expanded and the inner and outer chambers at the other end to be expanded and contracted respectively, means to connect said first inner chamber to a source of higher pressure and said first end chamber to a source of lower pressure to impress a differential pressure on the diaphragm between said chambers to open said valve and move said other diaphragm, an inlet into said second end chamber, a check valve in said inlet permitting flow only into said chamber, a connection between said second end chamber and second intermediate chamber, and an outlet from said second intermediate chamber.

15. In combination with a pump and storage tank therefor, an air charging means comprising a reciprocating pressure responsive element adapted for connection to the discharge and intake passages of said pump and motivated by the pressure differential generated by said pump when in operation, and a reciprocating air pump element connected to and motivated by said first element and having an air discharge passage adapted for connection to said tank.

16. An air charger for a pump and storage tank comprising, a body formed with relatively high and low pressure chambers, a movable element mounted between said chambers and displaced by the pressure differential therein, means for connecting said chambers to an external source of pressure differential, an air chamber in said body, a volumetric displacement member in said air chamber, means connecting said member to said element for joint movement, and an air intake and discharge means connected to said air chamber, said air discharge means being connected to said high pressure chamber.

17. In a pump and storage tank system, the combination of a pump having intake and discharge passages developing therebetween a pressure differential during operation of the pump; and an air charger comprising a body having relatively high and low pressure chambers, means for connecting said chambers to said pump passages, a movable element mounted between said chambers and displaced by the pressure differential therein, an air chamber in said body, a volumetric displacement member in said air chamber, means connecting said member and element, and air intake and discharge means connected to said air chamber, said air discharge means being connected to said pump discharge passage.

18. In a pump and storage tank system, the combination of a pump having intake and discharge passages developing therebetween a pressure differential during operation of the pump; and an air charger comprising a casing, a movable diaphragm mounted in said casing and defining therewith on opposite sides of said diaphragm a pair of chambers, means for connecting said chambers to said pump passages whereby during operation of said pump said diaphragm will be displaced in one direction by the pressure differential in said chambers, spring means for displacing said diaphragm in a reverse direction upon discontinuance of pump operation, a second movable diaphragm mounted in said casing and defining with said casing an air chamber, means connecting said diaphragms for joint movement, and air intake and discharge means connected to said chamber, said air discharge means being connected to said pump discharge passage.

19. In combination with a pump and storage tank therefor; a pump operated air charger for

said tank comprising, a casing having a passage therethrough, means for connecting said passage between the output of said pump and the intake of said tank, a pressure responsive element in said casing communicated on one side of said element with said passage and defining with said casing a chamber on the opposite side of said element, means for connecting said chamber to said pump at a fluid point having a relatively lower pressure during operation of said pump than said pump output whereby during operation of said pump said element will be displaced by the pressure differential in said passage and said chamber in the direction of said chamber, means for displacing said element in a reverse direction upon discontinuance of pump operation, an air chamber in said casing, a volumetric displacement

member in said air chamber, means connecting said member and said element for joint movement, air intake means for said air chamber, and air discharge means connecting said air chamber with said casing passage.
